UNITED STATES PATENT OFFICE.

FRED D. HOLDSWORTH, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

AIR-COMPRESSOR.

1,248,120.

Specification of Letters Patent. Patented Nov. 27, 1917.

Application filed May 8, 1912. Serial No. 695,875.

To all whom it may concern:

Be it known that I, FRED D. HOLDSWORTH, a citizen of the United States, and a resident of Claremont, county of Sullivan, and State of New Hampshire, have invented an Improvement in Air-Compressors, of which the following description, in connection with the accompanying drawings, is a specification, like characters on the drawings representing like parts.

This invention relates to elastic fluid compressors, and more particularly to compressors of the multi-stage type.

In the operation of air compressors which are driven by an external source of power which runs at a constant speed, such as electric motors, gas or gasoline engines, in order to maintain a constant air pressure, it is necessary to interrupt the flow of air through the machine when the pressure in the receiver reaches the desired point, and reestablish the flow as soon as the pressure in the receiver has fallen a few pounds. This is usually accomplished by placing a balanced valve, commonly called an unloading valve, on the main inlet supply to the compressor and attaching to this valve a suitable piston, which moves the valve to its open or closed position by means of a small regulator which is piped to the main air receiver. When this unloading valve is closed by the rise in the receiver pressure, the compressor rapidly forms a more or less complete vacuum in all of its internal air passages. Owing to the construction of this form of unloading valve, it is impossible to make it absolutely air-tight when it is closed, so that a small quantity of air flows through the machine, which air has to be compressed and delivered to the main receiver. Instead of compressing this air from ordinary atmospheric pressure, however, it may be compressed from only one or two pounds absolute pressure up to receiver pressure. This greatly increases the ratio of compression, and as the heat generated in compression is directly dependent upon the number of times the air is compressed, it will readily be seen that when the air reaches its final pressure in the air-cylinder, it will be heated very much in excess of the temperature obtained in compression under normal running conditions with the inlet-opening wide open. This

high temperature is detrimental to the oil used for lubrication, and is a source of danger, inasmuch as the extreme heat may ignite the oil, or if the oil is diffused through the air in proper proportions, an explosion may result. This is especially true of multi-stage compressors where the pressure is carried to several hundred pounds per square inch. This invention is more particularly concerned with the provision of an auxiliary unloading valve which may be employed in connection with the second or high-pressure cylinder of a two-stage compressor, or with the second and third cylinders of a three-stage compressor, or to the succeeding cylinders of a compressor of any desired number of stages.

In my co-pending application Serial No. 695,876, of even date herewith, I have disclosed an elastic fluid compressor similar in its general characteristics to my present invention but specifically different therefrom, and in that application I have claimed my invention broadly in such a manner as to dominate the present application.

My invention will be best understood by reference to the following description, when taken in connection with the accompanying illustration of one specific embodiment thereof while its scope will be more particularly pointed out in the appended claims.

In the drawings:

Figure 1 is a central longitudinal vertical section partly in elevation of a compressor embodying my invention;

Fig. 2 is a cross-sectional view of the compressor on line 2-2 of Fig. 1;

Fig. 3 is a longitudinal vertical section at an enlarged scale of one end of the high-pressure cylinder, which in the present embodiment is of the double-acting type, the front end being precisely similar in construction. This view shows the position of the auxiliary unloading valve under normal running conditions; and

Fig. 4 is a sectional view partly in elevation similar to Fig. 3, showing the auxiliary unloading valve in its open position, as it appears when the main unloading valve closes.

Referring to the drawings and to the em-

bodiment of my invention which I have there disclosed, for illustrative purposes, I have there shown a multi-stage compressor, herein having two cylinders, a low-pressure cylinder 5 and a high-pressure cylinder 6, the former drawing its supply from an inlet pipe 7 into an inlet chamber 8, and delivering the compressed air into an outlet chamber 9, connected by a pipe 10 to an intermediate receiver 11, which as is usual cools the air before it passes to the high-pressure cylinder. This receiver, which is commonly called an inter-cooler, delivers the air into an inlet chamber 12 of the high-pressure cylinder 6, whence it passes to an outlet chamber 13, as will appear hereinafter. This outlet chamber in practice is connected to a main receiver which I have not shown herein as it is unnecessary to the illustration of my present invention. The main inlet 7 may be controlled as is usual by means of a main unloading valve 14 of the balanced type. This valve is usually controlled by a suitable piston which moves the valve to its open or closed position by means of a small regulator which is piped to the main air receiver, these parts being of usual and well-known construction, and a further description of them being unnecessary to an understanding of my present invention.

The auxiliary unloading valve which forms the subject matter of my present invention may be applied to any cylinder of a multi-stage compressor beyond the first, or low-pressure cylinder,—that is to say, it may be applied to the second or high-pressure cylinder of a two-stage compressor, or to the second and third cylinders of a three-stage compressor, but for the present purposes, it will be convenient to describe the same in connection with the second or high-pressure cylinder of a two-stage compressor.

Referring now to Figs. 3 and 4, I have there shown one end of the high-pressure cylinder 6, herein of the double-acting type, the other end being precisely similar in construction. This cylinder is provided with a head 15, in which is located an inlet valve 16, which may be of any usual or desired construction, the same being herein of the oscillating type, being given an oscillating motion at the proper intervals in the operation of the machine by suitable mechanism connected with the crank-shaft. (See Fig. 1). The cylinder is also provided as usual with a discharge valve 17, which may be of any usual construction, herein being provided with a spring 18 tending to seat the same and operating as usual to open and permit the air compressed in the cylinder to flow into the outlet chamber 13, and thence to the usual main air receiver. Within the cylinder 6 is a usual piston 19, which when moved toward the right (Fig. 3) draws the air through the inlet chamber 12 and its

connections with the low-pressure cylinder 5, and upon the closing of the inlet valve 16, as shown in Fig. 4, the piston moves toward the left, thereby compressing the same in the usual manner; and when the pressure in the cylinder is equal to or slightly greater than the pressure in the discharge chamber 13, the discharge valve 17 will lift from its seat and allow the air to be forced out of the cylinder. To prevent the formation of a more or less complete vacuum when the unloading valve 14 on the main inlet 7 closes, I have provided a valve 20 which is adapted to open or close a port 21 leading from the interior of the cylinder 6 to the inlet chamber 12. This valve may be of any suitable construction, but I have herein chosen to employ for this purpose a hollow shell which is guided on a suitable guide, herein a plug 22. Suitable provision is made for allowing the pressure within the inlet chamber 12 to be exerted on the valve 20 in such a manner as to tend to seat the same, the plug 22 being herein provided for this purpose with vent openings 23 and 24. Suitable means are provided for controlling this valve herein a piston 25 mounted in a suitable cylinder 26 and having a piston-rod 27 engaging the valve. This piston-rod is herein provided with a passage 28, which maintains in the space 29 at the left-hand end of the cylinder 26 the same pressure as exists in the inlet chamber 12. Therefore, assuming that a pressure above atmospheric pressure normally exists within the inlet chamber 12, the inlet valve 20 will be seated by the action of the pressure acting thereagainst, as well as against the left-hand end of the piston 25. This may be assisted however, if desired, by means of a spring 30 bearing against the piston 25, and tending to keep the piston-rod 27 pressed against the valve 20, which in turn is pressed against its seat.

Within the cylinder 26, there is provided a space 31 at the right-hand side of the piston (Fig. 3), this space communicating with the atmosphere through a vent-hole 32.

The diameter of the piston 25 and the tension of the spring 30 may be so proportioned that they will hold the valve 20 seated against the maximum pressure within the cylinder acting against the end of the valve through the port 21, tending to raise the valve. Assuming now that the unloading valve on the main inlet closes due to the fact that the pressure in the main receiver has reached the desired limit and that in consequence of the removal of the air in the inlet space 12 by the action of the piston 19, the pressure in this space will fall below normal; as the interior of the valve 20 and the space 29 at the left of the piston 25 are in communication with the space 12, the pressure in these spaces will likewise fall. The

piston 19 in the cylinder 6, meanwhile, is traveling toward the left and compressing the air trapped within the cylinder up to a point where the reduced pressure on the 5 valve 20 and its piston 25 and the tension of the spring 30 is no longer sufficient to keep the valve seated. The valve will then rise, and instead of the air being discharged through the regular discharge valve 17, it will simply flow back into the space 12 10 through the port 21, so that instead of compressing the air up to the final terminal pressure, it will be compressed but a comparatively few pounds and returned to the space 12 to pass again into the cylinder on the suction stroke, this process being repeated as long as the unloading valve on the main inlet remains closed. In the meantime, no air 15 is being discharged from the machine into the main receiver, and as some air is bound to leak in around the unloading valve on the main inlet and from other sources of leakage, there will be an accumulation of air in the machine which will gradually raise the 20 pressure in the inlet space 12. When this pressure rises above the point where the pressure within the interior of the valve 20 and in the space 29 is more than sufficient to overcome the pressure in the main cylinder 6, 25 acting on the end of the valve from the port 21, the valve will be forced to its seat, and when this occurs the excess air will be discharged through the discharge valve 17.

It will be understood from the foregoing 30 that the auxiliary valve acts automatically to prevent diminution of pressure in the connections between the high and low-pressure cylinders to a point below atmospheric pressure when the main unloading valve closes, 35 or in other words, the valve acts automatically to place the high-pressure cylinder in communication with the connections between the cylinders when the pressure within said connections falls below normal. It will also 40 be seen that when the valve is applied to any cylinder beyond the intake-cylinder, when the unloading valve on the main inlet opens, the first cylinder will begin to receive air, and will compress the same into the next succeeding cylinder; this will quickly build up 45 the pressure in the passages between the two cylinders, and will thus furnish a motive force sufficient to close the auxiliary unloading valve.

50 While I have herein shown and described one form of my invention for illustrative purposes, and have disclosed and discussed in detail the construction and arrangement incidental to one specific application thereof, it is to be understood that the invention is 55 limited neither to the mere details or relative arrangement of parts, nor to its specific embodiment herein shown, but that extensive deviations from the illustrated form 60 or embodiment of the invention may be

made without departing from the principles thereof.

Having thus described one embodiment of my invention, what I claim is:—

1. In a multi-stage elastic fluid compressor, the combination of a plurality of compressor units, each having a cylinder and a piston, and one delivering to another, of an unloading valve for the inlet of one of said compressor units, an inlet valve for the 70 succeeding compressor unit, the cylinder of said succeeding compressor unit having a port communicating with the connections between the compressor units, a valve for said port normally held seated by the pressure within said connections, and means operated by atmospheric pressure to release the last-mentioned valve and allow the same to open under the influence of pressure in said cylinder when the pressure within said 75 connections falls below normal.

2. In a multi-stage elastic fluid compressor, the combination of a plurality of compressor units each having a cylinder and a piston, and one delivering to another, of an unloading valve for the inlet of one of said compressor units, an inlet valve for the succeeding compressor unit, the cylinder of said succeeding compressor unit having a port communicating with the connections between the compressor units, a valve for said 90 port, yielding means normally tending to seat the last-mentioned valve, and means operated by atmospheric pressure to act against said yielding means to release the last-mentioned valve and allow the same to open under the influence of pressure in said cylinder when the pressure within said 95 connection falls below normal.

3. In a multi-stage elastic fluid compressor, the combination of a plurality of compressor units each having a cylinder and a piston, and one delivering to another, of an unloading valve for the inlet of one of said compressor units, an inlet valve for the 105 succeeding compressor unit, the cylinder of said succeeding compressor unit having a port communicating with the connections between the compressor units, a valve for said port, yielding means coöperating with 110 the pressure within said connections normally tending to seat the last-mentioned valve, and means operated by atmospheric pressure to act against said yielding means to release the last-mentioned valve and allow the same to open under the influence of pressure in said cylinder when the pressure within said 115 connections falls below normal.

4. In a multi-stage elastic fluid compressor, the combination of a plurality of compressor units each having a cylinder and a piston, and one delivering to another, of an unloading valve for the inlet of one of said compressor units, an inlet valve for the 125 succeeding compressor unit, the cylinder of 130

4
said succeeding compressor unit having a port communicating with the connections between the compressor units, a valve for said port, yielding means normally tending 5 to seat said valve, and means normally operated by pressure within said connections and coöperating with said yielding means to hold said valve seated and adapted to be operated by atmospheric pressure to act 10 against said yielding means to release the last-mentioned valve and allow the same to open under the influence of the pressure in said cylinder when the pressure within said connections falls below normal.

15 5. In a multi-stage elastic fluid compressor, the combination of a plurality of compressor units each having a cylinder and a piston, and one delivering to another, of an unloading valve for the inlet of one of said compressor units, an inlet valve for the succeeding compressor unit, the cylinder 20 of said succeeding compressor unit having a port communicating with the connections between the compressor units, a hollow valve for said port, a guide for said valve having a passage forming communication between the interior of the latter valve and said connections, a piston for controlling the last-mentioned valve, a cylinder for said valve-actuating piston communicating on one side of the latter with the atmosphere, and a piston-rod also guided by said guide and having a passage forming a communication between the other side of the last-mentioned cylinder and said connections.

25 30

last-mentioned cylinder and said connections.

6. In a multi-stage elastic fluid compressor, the combination of a plurality of 35 compressor units each having a cylinder and a piston, and one delivering to another, of an unloading valve for the inlet of one of said compressor units, an inlet valve for the succeeding compressor unit, the cylinder 40 of said succeeding compressor unit having a port communicating with the connections between the compressor units, a hollow valve for said port, a guide for said valve having a passage forming communication between the interior of the latter valve and said connections, a piston for controlling the last-mentioned valve, a cylinder for said valve-actuating piston communicating on one side of the latter with the atmosphere, and a piston-rod also guided by said guide and having a passage forming a communication between the other side of the last-mentioned cylinder and said connections.

In testimony whereof, I have signed my 55 name to this specification, in the presence of two subscribing witnesses.

FRED D. HOLDSWORTH.
